UNDERFEED STOKER

Edward B. Birkenbeuel, Portland, Oreg., assignor
to Iron Fireman Manufacturing Company,
Portland, Oreg.

Application August 27, 1934, Serial No. 741,582

3 Claims. (Cl. 110—162)

This invention relates generally to stokers, and particularly to underfeed stokers.

The main object of this invention is the construction of a coal burning stoker which will be inexpensive to construct and maintain, and which will not discharge gas or dust into the furnace room, regardless of operating or atmospheric conditions.

The second object is the provision of a novel form of draft arrangement and means for delaying the commencement of each air-supplying operation for a fixed interval of time after the commencement of a corresponding fuel-supplying operation.

These, and other objects, will become more apparent from the specification following as illustrated in the accompanying drawing, in which:

Fig. 1 is a perspective view of the device showing the wiring in diagram.

Fig. 2 is a section taken along the line 2—2 in Fig. 1 in which the stoker is not being operated.

Fig. 3 is a view similar to Fig. 2 in which the stoker is being operated, and

Fig. 4 is a view similar to Fig. 3 showing the stoker operating but with the air supply automatically reduced.

Similar numbers of reference refer to similar parts throughout the several views.

Before entering into an explanation of this invention it will be understood that coal burning stokers have long been constructed in which a forced draft is supplied with the fuel which will, under certain conditions, produce a pressure within the combustion chamber in excess of that of the surrounding atmosphere, thereby causing gas and ashes to be blown from the furnace into the furnace room. A further difficulty which is always present with this type of underfeed stokers resides in the smoking or gassing through the coal hopper, due to the positive pressures existing within the plenum chamber, which difficulty is laid to the use of auxiliary air lines, closed hoppers, and other expedients for the purpose of preventing gassing.

In the invention which I am about to describe a negative pressure is maintained within the combustion chamber by the use of an exhaust fan in the smoke pipe of the furnace, thereby positively insuring against the leaking of dust outwardly from the furnace, and the discharge of gas or dust from the coal hopper.

It is not being claimed here that it is anything new to place a fan in a smoke pipe of a furnace, but that the application of an exhaust fan to the

smoke pipe of a furnace to which fuel is supplied by an underfeed stoker is entirely new.

Referring in detail to the drawing, there is shown a common form of warm air furnace 10 into the combustion chamber of which projects 5 the retort 11 of an underfeed stoker to which coal is fed through the tube 12 from a hopper 13 by means of a fuel feed worm 14 which is driven through suitable gearing in the transmission 15 by means of a motor 16. The motor 16 is controlled by means of a thermostat 17, or other form of switch placed in the circuit 18.

Surrounding the retort 11 is an air box 19 having an inlet opening 20 provided with double closures 21 and 22, both of which are hinged on 15 the pivot 23. The closures 21 and 22 are adjustably held in an angular relationship by means of the quadrant 24 and the clamp screw 25.

To the closure 21 is attached the rotatable screw 26 which may be operated by means of the head 27 on the outer side of the closure 21. The collar 28 is secured on the screw 26 on the inside of the closure 21 for the purpose of holding the screw 26 against endwise movement with relation to the closure 21.

Supported on the screw 26 is the under slung weight 29 through the upper end of which the screw 26 is threaded. The purpose of this construction is to permit the weight 29 to be adjusted with relation to the closure 21.

The smoke outlet 30 of the furnace 10 is connected to the centrifugal fan 31 whose discharge pipe 32 connects with the stack 33 provided with the usual clean-out 34.

The fan 31 is provided with a pulley 35 which 35 is driven by the belt 36 from the pulley 37 to the fan motor 38. The lead wires 39 of the motor 38 are connected to the time delay relay 40 which is energized through the wires 41 from the circuit 18.

Any suitable time delay relay 40 may be employed which will delay the commencement of the operation of the motor 38 after the commencement of the operation of the motor 16.

The operation of the device is as follows: Assuming that there is a call for heat at the thermostat 17, which may of course be in the room of a dwelling or any other place, it can be seen that the closing of the circuit 18 by the thermostat 17 will cause the operation of the motor 16, 50 and consequently the operation of the worm 14, which will feed coal upwardly into the retort 11. After a fixed interval of time, due to the operation of the time interval relay 40, the motor 38 will be energized and the fan 31 will cause the 55

products of combustion to be drawn from the furnace 10 and discharged into the stack 33.

If there are any leaks around the fire door 42, or the secondary air openings are not closed, then 5 air is positively drawn in through these leaks or openings, thereby insuring against a reverse condition if there should be a sudden change in the atmospheric conditions which would affect the natural stack pull.

- 10 It will be noted that until the fan 31 commences to operate, the closure 21 is in the position shown in Fig. 2 but the operation of the fan 31 will cause the closure 21 to move to the position shown in Fig. 3 in which the required amount 15 of air is admitted to the combustion chamber. If, however, for any reason, such as a speeding up of the fan or a low coal level in the retort, the velocity of air passing through the opening 20 increases, then the closure 22 will move toward 20 a closing position (as shown in Fig. 4) making the device self-regulating, while the closure 21 provides automatic banking when the stoker is shut down.
- 25 It can be seen from the foregoing that by this simple arrangement it is possible to burn coal without permitting any dust or gas to escape from the furnace into the furnace room.

I claim:

1. The combination with an underfeed stoker including thermostatically controlled coal feeding means and a retort, of a furnace, an exhaust fan in the smoke pipe of said furnace, and means for delaying the commencement of each fan operation until after the commencement of each fuel feeding operation. 5

2. The combination of claim 1, together with an air duct leading to the retort, and a double 10 damper for limiting the flow of air thru said duct while the fan is operating and for preventing the flow of air therethrough when said exhaust fan is not operating.

3. In combination, a furnace, a retort for heating said furnace, motor driven means for feeding coal to the retort, an air duct leading to said retort and having an inlet opening, a damper having two connected closures mounted so that each of the closures may move to a position to close 20 said inlet opening, a blower having its suction side connected to the furnace smoke pipe, an electric circuit, including a room thermostat, for operating the motor and the blower, and means for delaying the operation of the blower until after the 25 coal feeding means has operated thru a time interval.

EDWARD B. BIRKENBEUEL.
